UNITED STATES PATENT OFFICE.

JAMES E. LUSCOMB, OF NEW YORK, N. Y., ASSIGNOR TO MARY ROONEY, OF SAME PLACE.

BOX FOR BOTTLES.

SPECIFICATION forming part of Letters Patent No. 271,087, dated January 23, 1883.

Application filed November 23, 1882. (No model.)

To all whom it may concern:

Be it known that I, JAMES E. LUSCOMB, a citizen of the United States, residing at New York, in the county and State of New York, have invented new and useful Improvements in Boxes for Bottles, of which the following is a specification.

This invention relates to certain improvements in the construction and arrangement of the partitions of cases or boxes for holding and transporting bottles, as hereinafter fully set forth.

This invention is illustrated in the accompanying drawings, in which Figure 1 represents a plan or top view, partly in section. Fig. 2 is a vertical cross-section. Fig. 3 shows a portion of one side of the box, partly in section. Fig. 4 is a perspective view, showing one of the joints of the partitions.

20 Similar letters indicate corresponding parts.

The letter A designates the sides, B the ends, and C the bottom, of the box. D indicates longitudinal partitions, joined to the box-ends; and E, transverse partitions, joined to the box-sides. Said partitions D E are composed of sheet metal—as, for example, sheet-iron—and they are interlocked at the points of intersection by means of slots o, which, in the longitudinal partitions, extend upward from their lower edges, and in the transverse partitions extend downward from their upper edges, so that the longitudinal partitions rest on the other or transverse partitions; but it is evident that the arrangement of the slots can be reversed. For the purpose of joining the partitions D E to the box sides and ends, the parts last named are provided with vertical mortises s, which extend upward from the bottom of the box, so that they are closed at the lower ends by means of the bottom, the ends of the partitions being inserted in the proper mortises before the bottom is fastened in place. When the partitions D E have been interlocked they are swaged or indented on the upper edges, at the points of intersection, by a suitable tool, whereby the open ends of the slots in the transverse partitions are forced upon the edges of the longitudinal partitions,

50 forming burrs i, as indicated in Figs. 2 and 4, and by this means a very firm joint is produced between the partitions. The transverse partitions E are bent laterally at each end to form lips or blades l, and the vertical edges of such lips are provided with barbs l', (see Fig. 3,) projecting in a downward direction. When 55 the partitions are introduced into the mortises s the lips l are driven into the wood composing the box-sides, adjacent to the proper mortises, and by the action of the barbs l' said partitions are effectually prevented from moving in a downward direction, so that they are adapted to be brought above the bottom of the box, leaving a space beneath them, without danger of sinking by the weight of the longitudinal partitions, or from any other cause. 60 Said space left beneath the partitions is for the purpose of allowing the flow of waste liquid, and to permit the escape of such liquid openings are made in the box-bottom.

What I claim as new, and desire to secure by Letters Patent, is—

1. The longitudinal partitions having the slots projecting upward from the lower edges, and the transverse partitions having the slots projecting downward from the upper edges, and 75 having the open ends of such slots provided with the burrs i, in combination with the box sides and ends, having mortises s to receive the partitions, substantially as described.

2. The longitudinal partitions having the 80 slots extending upward from the lower edges, and the transverse partitions having the slots extending downward from the upper edges to support the longitudinal partitions, and having the lips l, provided with downwardly-projecting barbs l', in combination with the box sides and ends, having mortises to receive the partitions, substantially as described.

In testimony whereof I have hereunto set my hand in the presence of two subscribing 90 witnesses.

JAMES E. LUSCOMB.
